UNITED STATES PATENT OFFICE

166,418

PLANTER OR SIMILAR ARTICLE

Raymond C. Sandkuhle, San Jose, Calif.

Application November 26, 1951, Serial No. 17,521

Term of patent 14 years

(Cl. D35—3)

To all whom it may concern:

Be it known that I, Raymond C. Sandkuhle, a citizen of the United States, residing at San Jose, in the county of Santa Clara and State of California, have invented a new, original, and ornamental Design for a Planter or Similar Article, of which the following is a specification, reference being had to the accompanying drawing, forming a part thereof.

In the drawing: The single figure is a perspective view of a planter or similar article showing my new design.

I claim:

The ornamental design for a planter or similar article, as shown:

RAYMOND C. SANDKUHLE.
